DESIGN FOR A SHOE

Nathan Mitchell, New York, N. Y.

Application September 7, 1944, Serial No. 115,214

Term of patent 3½ years

(Cl. D7—7)

To all whom it may concern:

Be it known that I, Nathan Mitchell, a citizen of the United States of America, residing in New York city, county of Kings, and State of New York, have invented a new, original, and ornamental Design for a Shoe, of which the following is a specification, reference being had to the accompanying drawing, forming part thereof, wherein,

I claim:

The ornamental design for a shoe, substantially as shown.

NATHAN MITCHELL.
